DESIGN FOR A RECEPTACLE BASE FOR AN ELECTRICAL CONNECTOR

Alfred L. W. Williams, Cleveland Heights, Ohio,
assignor to The Brush Development Company,
Cleveland, Ohio, a corporation of Ohio

Application March 20, 1939, Serial No. 33,697

Term of patent 14 years

To all whom it may concern:

Be it known that I, Alfred L. W. Williams, a subject of the King of England, residing at 12415 Fair Hill Road, Cleveland Heights, in the county of Cuyahoga and State of Ohio, have invented a new, original, and ornamental Design for a Receptacle Base for an Electrical Connector, of which the following is a specification, reference being had to the accompanying drawing, forming part thereof.

Fig. 1 is a front elevational view of a receptacle base for electrical connector showing my new design.

Fig. 2 is an end elevation.

Fig. 3 is a side elevation.

Fig. 4 is a sectional elevation taken on the line 4—4 of Fig. 1; and

Fig. 5 is a transverse sectional view taken on the line 5—5 of Fig. 1.

I claim:

The ornamental design for a receptacle base for an electrical connector, substantially as shown.

ALFRED L. W. WILLIAMS.
